UNITED STATES PATENT OFFICE.

PETER GRAY, OF SAN FRANCISCO, CALIFORNIA.

VENTILATING DEVICE.

1,201,172.

Specification of Letters Patent. Patented Oct. 10, 1916.

Application filed March 13, 1914. Serial No. 824,450.

To all whom it may concern:

Be it known that I, PETER GRAY, a citizen of the United States, residing at 2711 Union street, San Francisco, in the county of San

Francisco, State of California, have invented new and useful Improvements in Ventilating Devices, of which the following is a specification.

My invention relates to improvements in 10 "ventilating devices", suitably adapted to be used on ships or vessels, but also adapted for use in any place needful of ventilation.

The object of my invention is to provide a 15 device, so designed, when combined that it will supply fresh air and simultaneously expel the spent air.

My invention consists of a combination 20 of parts, comprising an intake piece for fresh air, a body portion segregating the fresh air and spent air, a base portion directly attached to said body portion, this base portion connecting with said body portion and forming an elongation of same, and 25 being further adapted to be attached to a divided attachment provided to connect with the fresh air supply part, and the spent air discharge part, and this base portion being further supplied with a flange or other 30 suitable means adapting it to be attached to any suitable place.

In reference to the sheets of drawings, forming part of this specification, the mode 35 of operation will be fully and clearly set forth and similar numbers of reference indicate like parts.

Figure 1 is an external elevation of ventilating device. Fig. 2 is a vertical section of same. Fig. 3 is a horizontal section taken 40 on line A—A. Fig. 4 is a horizontal section taken on line B—B. Fig. 5 is an elevation of the air segregating body portion. Fig. 6 shows a broken view of said ventilating device, partly in section, showing the arrangements or means for segregating the fresh 45 from the spent air.

By reference to Fig. 1, it is seen that the apparatus here illustrated comprises the intake piece 1 for fresh air in one continuous 50 piece down to and including part of the operating mechanism 2, whereby said intake piece 1 may be revolved in any desired direction, this operating mechanism 2 may be of several kinds, or none at all, as the friction of parts may be relied on to maintain 55 the intake piece 1 in a relatively fixed posi-

tion to other parts of ventilating device. In this view, there is also partly shown the external part of body portion 3, likewise the base portion 4.

The intake piece 1 consists of an air collecting funnel 16 adapted to be turned toward the moving air current to direct the fresh air into the apartments to be ventilated, and a lower cylinder part or section 17 surrounding the upper part of the body portion 3. A transverse partition 18 divides the intake piece at about the plane of the junction of the portions 16 and 17 forming two separated chambers. In order that the 70 intake piece may be supported so as to be freely revolved it is provided with an upper cylindrical bearing 20 above the partition 18 and a lower cylindrical bearing 21, the latter being at the lower end of the intake 75 piece and below an inwardly flaring section 19 thereof. To this latter bearing is secured the gear ring 2 constituting part of the turning mechanism for the intake piece. The upper bearing 20 which is preferably formed 80 by a flange extending upwardly from the transverse partition 18 is closed by a cover piece 22 that is perforated to permit the free passage of the fresh air taken in through the air collecting funnel 16. The 85 partition 18 and cover piece 22 with the cylindrical part that constitutes the bearing 20 may together be considered as the transverse partition dividing the intake piece.

A hood 5 is supported above the cover 90 piece 22 and protects the openings therein from rain or other form of condensed moisture that may enter the funnel. Any water that collects upon and is shed by the hood flows into an annular channel formed between the bearing 20 and the adjacent wall of the funnel 16, where it collects upon the partition 18 and whence it is carried off through drain pipes 6 that deliver into the 95 open, these extending preferably from the 100 partition 18 to the flaring section 19 of the intake piece, in which parts they have bearing so as to be firmly supported. In the lower part of the intake piece are formed a number of openings 7 that serve as the outlets for the spent air, these being preferably located all around the intake piece, in the flaring section 19, and, if desired, in the lower part of the cylindrical section 17 of the intake piece, as clearly shown in Figs. 116 1, 2 and 6.

As already stated the gear ring 2 is at-

tached to intake piece 1, and is operated by a pinion 8, mounted on a spindle 9, supported by suitable brackets 14, mounted on body portion 3; the spindle 9 with pinion 8 being operated by a lever 10, and thus by this means, the relative position of intake piece 1 to that of body portion 3 may be changed.

The body portion 3 of the apparatus is formed with a lower portion 24, preferably cylindrical in shape, and adapted to have a telescopic connection with the base portion 4, that is fixed to the structure to which the ventilating apparatus is applied, as by means of its securing flange 11. The body portion 3 is also formed with an upper cylindrical portion 25 that registers telescopically with and serves as a support for the bearing 20 of the intake piece 1. Likewise the lower bearing 21 of the intake piece engages with and is supported by the upper part of the lower portion 24 of the body portion 3. In an apparatus constructed as represented in the drawings the lower cylindrical portion 24 is approximately half the length of the entire body piece 3, and extends from the supporting flange 11 of the base piece 4 to a little above the upper edge of the bearing 21 of the intake piece. It is divided by a transverse partition 23 to form two ducts or passages, one, 15, for the fresh air, and the other, 12, for the spent air. The partition 23 continues above the cylindrical portion 24, forming with the opposing wall 27 a half cylindrical duct that is a continuation of the duct 15, and is, in its upper part, curved, as indicated at 26, so as to join the cylindrical part 25 at its edge or periphery. This arrangement provides a closed fresh air duct 15 leading from the openings through the cover 22 below the hood 5 to the lower end of the body piece 3; and a spent air duct 12 separated from the fresh air duct by the partition 23 and leading from the lower end of the body piece 3 to the upper end of the cylindrical portion 24 thereof where the duct 12 opens into the chamber within the intake piece formed by the cylindrical part thereof below the transverse partition 18. From this chamber the spent air may freely escape through the opening 7. It will thus be seen that while the body piece 3 of the apparatus is stationary and the intake piece 55 freely revoluble relative thereto, the two passages or ducts, one for the fresh air and the other for the spent air, are quite distinct one from the other, and that the fresh air is delivered to one and the spent air escapes from the other with equal facility in whichever direction the funnel of the intake may be turned.

It will be seen by reference to Figs. 2 and 6 that the base piece 4 is divided by a transverse partition 27 that is adapted to register

with the partition 23 and continue the separation of the fresh and the spent air passages through this base piece. In order to insure that these partitions shall properly register, as well as to prevent any relative movement of the parts 3 and 4 after the apparatus is assembled, the cylindrical part 28 thereof is slotted, at 29, beyond the partition 27 to receive the lower edge of the partition 23, as clearly represented in Figs. 3 and 6. In order that the superposed parts of the apparatus may be firmly supported the cylindrical portion 24 of the body piece 3 extends beyond the end of the partition 23 so that the lower edge of the former rests upon the flange 11 of the base piece, while the lower edge of the partition 23 meets the upper edge of the partition 27, the former resting in the slots 29.

13 is an attachment below the base piece 85 and consisting of two air trunks or ducts, 12', 15', for the spent air and the fresh air, respectively, these leading from the base piece 4 to the compartment or section of the structure whose ventilation is controlled by the particular apparatus with which they connect. The attachment 13 comprises, besides the two air ducts specified, a cylindrical coupling member 30 adapted to be connected with the base piece 4 as by a telescopic union with the flange 28 thereof. A partition 31 separates the fresh and the spent air ducts from that part of the attachment 13 where the two trunks 12', 15' merge. This partition registers with the partition 27 in the base piece 4, its edge resting in slots 29 corresponding with the slots for the partition 23. I have illustrated but two air trunks, one for the fresh air and one for the spent air leading from the base piece 4. It will be understood that this arrangement is merely illustrative of the invention and that if the requirements of the case demand a larger number of ducts, they will be provided in a manner well known to those familiar with the art of erecting ventilating apparatus.

I do not wish myself to be understood as claiming the special construction of parts as illustrated and described, but any practical and well adapted means, which will effect a successful operation of "ventilator," and coming within the claims of this specification will be utilized.

Having thus described my invention, what I claim and desire to secure by Letters Patent is:

1. In a ventilating apparatus, the combination of a stationary cylindrical tubular body, a partition dividing the said body into separate air ducts, one for incoming fresh air and the other for outgoing spent air, an intermediate portion of the said tubular body being cut away on one side of the partition, forming an opening for the spent

air duct, and dividing the tubular body into two cylindrical portions, and the upper part of the said partition being curved and united with the wall of the upper cylindrical portion of the said tubular body making it a part of the fresh air duct, the said upper cylindrical portion being open to the outside air, and a rotary intake piece supported on the said tubular body, such intake piece being provided with bearings that respectively engage with the upper and the lower cylindrical parts of the aforesaid stationary tubular body, and having its lower portion formed to constitute a chamber surrounding the cut-away portion of the said stationary tubular body piece, there being openings through the wall of the said chamber for the escape of the spent air, the intake piece having also a transverse partition dividing the said chamber from the outer intake portion thereof, the upper tubular bearing of the intake piece being carried by the said partition.

2. In a ventilating apparatus, the combination of a stationary body piece having a lower cylindrical portion and an upper cylindrical portion, these being connected by a parti-cylindrical wall, the lower cylindrical portion being divided into a fresh air 30 and a spent air passage by a partition, which partition is extended beyond the end of the lower cylindrical portion and joins the upper cylindrical portion, and, together with the said connecting wall, continues the fresh air 35 passage to the upper cylindrical part of the body piece, an intake piece having a fresh air collecting funnel communicating with the upper cylindrical part of the stationary body piece, and a cylindrical part surrounding the body piece between its cylindrical portions and forming a chamber with which communicates the spent air passage, the said chamber being separated from the funnel by a partition, and having formed in its walls 45 openings whereby it communicates with the open air, bearings carried by the intake piece engaging with the cylindrical portions of

the stationary body piece, permitting the intake piece to revolve on the stationary piece, a hood covering the openings between the 50 funnel and the upper cylindrical portion of the stationary part, and drains for carrying off water that may collect in the said funnel.

3. In a ventilating apparatus, the combination of a base piece of tubular construction divided by a partition into separate air passages, a superposed body piece of tubular construction adapted to fit upon the base piece with a telescopic joint, such body piece being divided by a transverse partition into 55 separated air passages, one for the incoming fresh air and the other for the outgoing spent air, the edges of the said partitions being adapted to come together when the pieces are assembled, and the said parts being 60 constructed to prevent rotative movements of one piece relative to the other after being assembled.

4. In a ventilating apparatus, the combination of a base piece of tubular construction having a partition dividing it into air passages for the fresh and the spent air, a body piece of tubular construction supported upon the base piece, the walls of these two pieces fitting together with a telescopic joint, 70 the body piece being divided into air passages by a transverse partition, the telescoping walls of one of the parts being slotted and the partition carried by the other part being adapted to enter the said slots 75 and to come into close registry with the edge of the partition carried by the other part, whereby the air passages in the two parts are continuous, and rotative movements of one relative to the other are prevented after 80 they are properly assembled.

In testimony whereof I affix my signature in the presence of two witnesses, this 21st day of February, 1914.

PETER GRAY.
